UNITED STATES PATENT OFFICE.

HEINRICH COLLOSEUS, OF BERLIN, GERMANY, ASSIGNOR TO WILLIAM ROSS WARREN, OF NEW YORK, N. Y., AND EDWARD JOHN VAVASOUR EARLE, OF LONDON, ENGLAND.

PROCESS FOR MANUFACTURING CEMENT FROM BLAST-FURNACE SLAG.

No. 12,801.

Specification of Reissued Letters Patent. Reissued June 2, 1908.

Original No. 837,918, dated December 11, 1906, Serial No. 251,446. Application for reissue filed February 29, 1908
Serial No. 418,621.

To all whom it may concern:

Be it known that I, HEINRICH COLLOSEUS, chemist and doctor of philosophy, a subject of the German Emperor, residing at 29 Pragerstrasse, in the city of Berlin, Kingdom of Prussia, and German Empire, have invented a certain new and useful Process for Manufacturing Cement from Blast-Furnace Slag, of which the following is a specification.

10 This invention has reference to the manufacture of cement from blast-furnace slag; and it consists in a process wherein an addition of solutions of calcium salts, aluminium salts, and magnesium salts is made to the 15 slag, according to its composition, on the discharge of the slag from the blast-furnace—that is to say, while it is yet in a liquid condition.

It is a well-known fact that blast-furnace 20 slag of the most usual compositions, both the flour-like powder as well as the powdered granulated slag, possesses hydraulic qualities; but these powders will set only after several days and either do not attain at all the 25 strength required of cement or, in the case of particularly favorable compositions of slags, only after some months, so that they cannot be regarded as cements proper, practically speaking.

30 My present invention consists in introducing into the liquid blast-furnace slag salts of lime, of alumina, or of magnesia, in solution, one or more of these, according to the proportion of lime, alumina, magnesia, and 35 silicic acid contained in the slag and according to the hydraulic qualities dependent thereon.

The process is carried out as follows: The 40 stream of liquid slag when it runs out from the blast-furnace is finely distributed, and at the same time an aqueous solution of calcium salts, of alum, of sulfate of magnesia, or of any other salt or salts of one or more of these 45 three metals is allowed to act upon this finely distributed slag. Water-vapor will then be evolved and also small quantities of vapors of sulfur dioxide formed by oxidation. The salts dissolved in the solution, whether 50 they are calcium, alum, or magnesium salts or all three together, combine apparently with the silicic acid, with the lime, and the alumina of the blast-furnace slag to form di and tri calcium, aluminium, or magnesium silicates. The sulfuric acid present in the

55 salts or produced by oxidation acts upon some of the calcium sulfid contained in the blast-furnace slag, so as to form the valuable calcium sulfate. The liberated water causes a rapid cooling of the slag which, results in a kind of clinker that resists the action of the 60 air, so that, particularly with foundry-iron slags, which are very rich in lime, a disintegration in air that would form the so-called "smelters' flour" is avoided. This slow disintegration destroys, largely or wholly the 65 cement-like qualities of the product. The vapor produced from the aqueous solution by the contact with the hot slag is a very efficient agent in effecting a disruption of the 70 slag which assists in incorporating the salts 75 with the hot slag. It is obvious that by a mere melting together of the alkaline-earth constituents of the salts with the slag this object of the change of physical properties can not be obtained, and it is not possible to 80 have the salts so finely distributed as to produce the decomposition desired. The thus treated slag is distinguished from the untreated slag, apart from its chemical composition, in the following points as regards 85 physical properties; first, as compared with the above-mentioned smelters' flour, disintegrated flour-like slag, and water granulated and air-treated slag, slags treated according 90 to the process herein described react considerably more readily; second, while the disintegrated flour, the dried water-granulated slag, and the air-treated slag of the most usual compositions either do not harden at all in most cases or only after some weeks, so 95 as to form a kind of cement, the slag treated according to the process herein described exhibits the physical behavior of a good Portland cement.

Chemically speaking, the slag treated according to the process stated differs from smelters' flour, disintegrated-slag flour, water-granulated slag, and slag that has undergone an air treatment by the fact that the sulfid of lime, which is generally contained in 100 very large quantities in the smelters' flour, in the water-granulated slag and in the air-treated slag is partly oxidized.

The amount of salts to be used varies with the composition of the particular slag. If, 105 for example, blast-furnace slag is to be treated containing approximately from twenty-six to thirty-two per cent. of silica,

from twelve to eighteen per cent. of alumina and iron, and from forty-five to fifty per cent. of lime, it is sufficient to inject into the freshly-prepared molten slag from six to ten per cent. of the solutions of salts containing, as an instance, about five per cent. of nitrate or sulfate or other suitable salt of the above-mentioned metals. It has, however, been found that slag containing a higher proportion of silica and less lime can also be made to harden in the same manner as cement—that is to say, it can also be used for the manufacture of cement, answering the necessary requirements if solutions containing a higher percentage of salt—for instance, up to ten per cent.—are injected, thus increasing the proportion of salts in relation to the slag. With slags of approximately the composition hereinbefore mentioned I prefer to use sulfide of magnesia alone in the majority of cases; but with slags of different composition the best salt or combination of salts for producing the desired result can only be ascertained by experiment. If the slag is thick in flowing or is not perfectly liquid, it is desirable to reduce the percentage of solution used, at the same time increasing its strength in proportion. The object of this is not to cool the slag too much in the operation.

I am aware that salts, and in particular sodium salts in a dry state, have been added to hot liquid slag in order to remove some impurities of the slag by mutual decomposition and subsequent skimming off the products of decomposition. This is, however, entirely different from my invention, inasmuch as in my invention the action involves a change of physical properties, as above outlined, and a very fine state of distribution of the salts and a disruption of the slag, due to the fact of adding the salts in aqueous solution, while the chemical reactions which are set up are also entirely different from those set up by the melting together of the reagents with the slag.

I am also aware that attempts have been made to improve the quality of slag cement by treating molten but not necessarily freshly-prepared and very highly heated slag with a mixture of lime and chlorid of lime, in which the lime is greatly in excess of the chlorid of lime, so as to form a paste of lime containing a small percentage of chlorid of lime, in order to increase the amount of lime to be incorporated with the slag; but this also is not the object of my invention, which aims to produce a product having the desired cement-like qualities without any subsequent addition of lime to the molten slag and merely by the changes set up by the dissociation produced upon the addition of the small quantities of solutions of salts of alkaline earths and of the earth metals to the slag, as above outlined, and without any further addition of alkaline or alkaline-earth oxides or

of any other ingredient not already present in the slag, with the exception of said salts.

What I claim, and desire to secure by Letters Patent of the United States, is—

1. The process herein described of manufacturing cement from blast-furnace slag, which consists in treating freshly-prepared hot liquid blast-furnace slag with a solution of any water-soluble salt of the earthy oxid-forming metals and without any further addition. 70

2. The process of manufacturing cement from blast-furnace slag which consists in acting upon freshly-prepared hot liquid blast-furnace slag with relatively small quantities 80 of the solution of any water-soluble salt of the earthy oxid-forming metals and without any further addition. 85

3. The process of manufacturing cement from blast-furnace slag which consists in acting upon freshly-prepared hot liquid blast-furnace slag with a solution of any water-soluble salt of the earthy oxid-forming metals, the slag being largely in excess of said solution, and without any further addition, 90 and then allowing the product to cool. 95

4. The process of manufacturing cement from blast-furnace slag which consists in acting upon freshly-prepared hot liquid blast-furnace slag with a solution of any water-soluble salt of the earthy oxid-forming metals, most deficient in the composition of the slag, the slag being largely in excess, and without any further addition and allowing the product to cool. 100

5. The process of manufacturing cement from blast-furnace slag which consists in acting upon freshly-prepared hot liquid blast-furnace slag with so much of a solution of any water-soluble salt of the earthy oxid-forming metals, the slag being largely in excess, as to avoid chilling of the slag during the operation, and without any further addition, and then allowing the product to cool. 105

6. The process herein described of manufacturing cement from blast-furnace slag, which consists in acting upon the hot liquid slag with a solution of any one or more water-soluble salts of the earthy oxid-forming metals, the specific quantity and character of 115 said solution being such with reference to the composition of the slag to be treated as to produce the desired cement-like qualities therein. 110

7. The process herein described of manufacturing cement from blast-furnace slag, which consists in treating the hot liquid slag while in a finely distributed state with a solution of any one or more water-soluble salts of the earthy oxid-forming metals, the specific quantity and character of said solution being such with reference to the composition of the slag to be treated as to produce the desired cement-like qualities therein. 120

8. The process herein described of manu-

facturing cement from blast - furnace slag, which consists in acting upon the hot liquid slag with a relatively small quantity of a solution of any one or more water soluble salts of the earthy oxid-forming metals, the specific quantity and character of said solution being such with reference to the composition of the slag to be treated as to produce the desired cement-like qualities therein.

10 9. The process herein described of manufacturing cement from blast - furnace slag, which consists in acting upon the hot liquid

slag with a solution of sulfate of magnesium, the specific quantity and character of said solution being such with reference to the composition of the slag to be treated as to produce the desired cement-like qualities therein. 15

In testimony whereof I have hereunto signed my name to this specification in the presence of two subscribing witnesses.

HEINRICH COLLOSET S.

Witnesses:

RICHARD EYRE,
EDWIN SEGER.

It is hereby certified that in Reissue Letters Patent No. 12,801, granted June 2, 1908, upon the application of Heinrich Colloseus, of Berlin, Germany, for an improvement in "Processes for Manufacturing Cement from Blast-Furnace Slag," an error occurs in the printed specification requiring correction, as follows: In line 53, page 1, after the word "and," a comma and the word *or* should be inserted; and that the said Letters Patent should be read with this correction therein that the same may conform to the record of the case in the Patent Office.

Signed and sealed this 16th day of June, A. D., 1908.

[SEAL.]

C. C. BILLINGS,
Acting Commissioner of Patents.
